UNITED STATES PATENT OFFICE.

FRED M. GOODHUE, OF BUFFALO, NEW YORK.

ALBUM LEAF OR LEAVES.

1,320,683.

Specification of Letters Patent.

Patented Nov. 4, 1914.

Application filed March 21, 1919. Serial No. 283,971.

To all whom it may concern:

Be it known that I, FRED M. GOODHUE, a citizen of the United States, residing at Buffalo, in the county of Erie and State of New York, have invented new and useful Improvements in Album Leaf or Leaves, of which the following is a specification.

This invention relates to display or album leaves and has as its object the provision of a simple and durable leaf or mount suitable for display and preservation of postage stamps, autographs, clippings and other articles of a similar nature which one might desire to preserve and at the same time display and inspect at frequent intervals.

Although the mount is shown in the drawings as used for the display of postage stamps it is obvious that the same might well be employed in connection with a large variety of articles and for a great many purposes such as the display of samples by merchants, and the preservation of records, photographs and other analogous objects.

Another aim of my invention is to permit the display of such articles as are mentioned above, in a manner that will allow examination without handling and possible injury, and permit preservation of the same protected from dust and decay but in a manner which at the same time allows ready removal, replacement or rearrangement with a minimum of wear and inconvenience.

The above and other objects which will become apparent as the description proceeds, I attain by constructing a two ply leaf comprising a transparent protective sheet, and a backing sheet joined thereto by spaced lines of stitching which form a plurality of pockets between the two sheets for the reception of the articles to be preserved. In order to provide ready access to the pockets I form in the backing sheet a number of elongated tongues or flaps which are adapted to swing outwardly from the body of the sheet to permit the insertion or removal of the articles; each flap, it being understood, registering with one of the pockets. I also desire to exclude dust and other destructive elements from the pockets and thereby more effectively protect the stamps; and to attain this end the flaps or tongues are of sufficient size to completely close the pockets when they are not swung outwardly from the backing sheet.

While I have shown my improved leaf as used in connection with postage stamps it

should be understood that stamps are mentioned in this specification and shown in the drawings as merely illustrative of a large number of articles with which this invention is adapted to be used.

In the accompanying drawings:

Figure 1 is a rear elevation of the backing sheet prior to the attachment of the protective sheet thereto.

Fig. 2 is a view similar to Fig. 1 but showing the backing sheet with the flaps raised and with the protective sheet attached.

Fig. 3 is an edge view of the backing sheet with the flaps raised as in Fig. 2.

Fig. 4 is a view of the protective sheet.

Fig. 5 is a front elevation of the completely assembled leaf ready for insertion into an album.

Fig. 6 is an edge view of the leaf as shown in Fig. 5.

Fig. 7 is an plan view showing two leaves joined together along their lateral edges and with their backs facing.

Similar characters represent like parts in the several views and referring to the same more in detail A indicates a rectangular base or backing sheet of cardboard, heavy paper or other suitable material having attached thereto, in the present instance by spaced horizontal and vertical lines of stitching e e', a protective sheet B of transparent or semi-transparent material such as paraffin paper, celluloid, silk, tracing cloth, etc. While I have employed stitching as a means of joining together the two sheets in the particular embodiment of my invention herein disclosed, it is obvious that there are a large number of means which could as well be used for joining these two sheets, such as fasteners and adhesive, the use of any of which is contemplated and comes within the scope of my invention.

It is necessary, however, in securing together the two plies of my leaf that the joining means be suitably spaced so as to form a plurality of pockets between the two sheets for the reception of the stamps. It is further to be observed that although I have shown upon each sheet only two lines of vertical sewing and these adjacent the periphery of the protective sheet their number and the distance separating them may be varied depending upon the size of the pockets desired.

In order to provide ready access to each of the pockets and at the same time to ef-

fectually close the same to dust and other elements, such as water and moisture which would have a destructive effect upon the stamps, slits may be cut in the backing sheet 5 either at the top or the side of the pockets or, in fact, in any location which might be desirable.

In the embodiment of my invention shown on the accompanying drawings, I provide 10 a form of opening for the pocket which has been found to be very satisfactory. I cut in one of the sheets; in the present instance the backing sheet, a number of elongated flaps or tongues *d*, having straight 15 lower edges merging into upwardly curving lateral edges. These flaps may be left integral with the backing sheet along one side or may be cut entirely from the backing sheet and then hingedly secured there- 20 to by means of stitching, adhesive strips, or any other suitable means. In the present embodiment of my invention the flaps are shown as integral with the backing sheet and adapted to swing outwardly therefrom 25 along a straight line joining the termini of the upwardly curved lateral edges of the flaps. When not swung outwardly and therefore lying within the plane of the backing sheet the flaps are adapted to entirely close 30 the pockets against dust and moisture thereby preserving the stamps in a most effective manner; and by reason of their hinged construction they may at the same time be readily raised permitting insertion, replacement 35 and arrangement of the stamps.

As shown in the several views the backing sheet is provided along one of its lateral edges with a marginal binding extension "g" rendering this sheet of somewhat 40 greater width than the protective sheet and affording means by which the leaf may be bound in a permanent volume or, as contemplated in the present instance, in a loose leaf binder; perforations *b* being made in 45 the margin for this purpose.

It is found that when a multiply leaf such as I have disclosed, in which the plies are of different areas, is placed in a book, binder, or album, the binding edge being 50 of less thickness than the remainder of the leaf the volume has a tendency to open up and is not of uniform thickness throughout. In order to overcome this objection I attach by adhesive or other suitable means 55 to the front face of the backing sheet along its binding margin "g" a filling strip *C* which by rendering the leaf along this edge of the same thickness as on its main portion makes the same more suitable for bind- 60 ing and the leaves when bound produce a more shapely volume.

In Fig. 7 I have disclosed what I have found to be a highly satisfactory method of incorporating these leaves in a binder 65 and forming a mount having two display

faces. In this figure there are shown two leaves such as I have described above, but having their binding margins on opposite lateral edges *i. e.*, one leaf is provided with a right hand binding margin and the other 70 with a left hand margin. The two leaves are placed with their backing or base sheets facing each other and are hinged together by means of a fabric strip "f" secured to the back of each leaf along its edge. When the two leaves are brought together with their backing sheets in contact by swinging the inner edges on the dotted line (Fig. 7), the binder perforations *b* of each leaf are in registration and the two leaves may then 80 be placed in the album. By inserting the leaves in the album in this manner the contact of the two sheets insures the closing of the flaps *d* thereby sealing the pockets and preventing tampering with the stamps 85 without removing the leaves from the volume.

I do not limit myself to this method of incorporating the leaves in a book or binder 90 but have found the same to be a most satisfactory way of using the leaves when constructed as described in this specification.

While I have disclosed a specific form 95 and construction for my improved leaf or mount I reserve the right to make such changes and modifications thereof as come within the scope of the following claims.

What I claim is:

1. In an album or display leaf, a transparent protective sheet, a backing sheet, 100 spaced means for securing together the two sheets forming pockets therebetween and openings in one of said sheets providing access to said pockets.

2. In an album or display leaf, a transparent protective sheet, a backing sheet, 105 spaced means for securing together the two sheets and forming pockets therebetween and openings in said backing sheet providing access to said pockets.

3. In an album or display leaf, an imperforate transparent protective sheet, a backing sheet, a plurality of pockets formed between said sheets, and a plurality of tongues 115 cut in said backing sheet adapted to be swung outwardly to provide access to said pockets.

4. In an album or display leaf, a transparent covering sheet, a backing sheet, means 120 securing together the two sheets and forming pockets therebetween and flaps cut in said backing sheet providing access to said pockets, said flaps being adapted to swing outwardly from said backing sheet but when not so swung completely closing the pockets 125 between the two sheets.

5. An album or display leaf as specified in claim 3 the backing sheet having a marginal extension whereby the leaf may be secured in a binder.

6. An album or display leaf comprising a transparent protective sheet, a backing sheet, spaced lineal joining means for said sheets forming pockets therebetween, and flaps in said backing sheet having straight lower edges merging into upwardly curved lateral edges providing access to said pockets and closures therefor.
7. An album or display leaf comprising a transparent protective sheet, a backing sheet, spaced lineal joining means for the two sheets forming pockets therebetween said backing sheet having openings providing access to said pockets, closures for said openings, a marginal binding extension on said backing sheet and a "filling" strip on the marginal extension of said backing sheet.
8. An album or display leaf comprising a transparent protective sheet, a backing sheet, spaced horizontal and vertical rows of stitching joining said sheets and forming a plurality of pockets therebetween, and openings in one of said sheets providing access to said pockets.
9. An album or display leaf comprising a protective sheet, a backing sheet, spaced lines of stitching joining said sheets and forming pockets therebetween, openings in one of said sheets providing access to said pockets, and closures for said openings whereby dust is excluded from the pockets.
10. In an album mount, two multi-ply leaves each leaf having a transparent protective sheet joined to a backing sheet by spaced means forming pockets between the two sheets, said leaves having their back sheets in contact, coinciding perforated binding margins on said leaves having their perforations in registration, and flexible means joining together the two leaves along their outer lateral edges.

In testimony whereof I have hereunto set my hand in presence of two subscribing witnesses.

FRED M. GOODHUE.
